UNITED STATES PATENT OFFICE.

AMOS D. ROOD, OF CHICAGO, ILLINOIS, ASSIGNOR, BY DIRECT AND MESNE ASSIGNMENTS, TO NETTA G. ROOD AND THOMAS B. BRYAN, BOTH OF SAME PLACE.

TYPE.

SPECIFICATION forming part of Letters Patent No. 408,195, dated July 30, 1889.

Application filed February 19, 1889. Serial No. 300,482. (No model.)

To all whom it may concern:

Be it known that I, AMOS D. ROOD, a citizen of the United States, residing at Chicago, in the county of Cook and State of Illinois, 5 have invented a new and useful Improvement in Type, of which the following is a specification.

My invention relates to type for printing characters through the medium of ink, whether 10 used in a printing-press, a type-writing machine, a hand-stamp, or otherwise. The various type-impressions made with ink are liable to be more or less fugitive, are frequently indistinct, and are susceptible of effacement, wholly or in part, and even of alteration; and my object is to overcome these 15 defects by imparting to the impression a quality of especial permanency.

To this end my invention consists in providing the salient portion of the type with puncturing-points, sufficiently close together to produce by perforations in the material printed upon an outline of the character imprinted by means of the ink—that is to say, 20 my invention consists in a type for transferring to the material printed upon a twofold reproduction of the character upon the type, the one by means of ink, as usual, and the other by means of perforations, so that each 25 reproduction serves to confirm the other, and at the same time exceptional permanency is secured, since the perforated outline is incapable of effacement or alteration without readily-apparent injury to the material.

30 In the accompanying drawings, Figure 1 is a plan view of a type provided with my improvement; Fig. 2, a sectional view of the same, taken on the line 2 2 of Fig. 1; and Figs. 3 and 4, similar sectional views showing modifications in the matter of the location of the puncturing-points.

35 A is a type, comprising the usual body *t*, with the character *s* in relief upon its end. At intervals upon the end of the type punct-

uring-points *p* are formed, which may either 45 be centrally located upon the face of the character, as shown in Figs. 1 and 2, or upon or along one or both margins of the face, as indicated in Figs. 3 and 4.

My invention is not to be confounded with 50 the ordinary puncturing hand-stamps, nor with the perforating-type which have the outline of the character or figure to be transferred formed upon them by puncturing-points alone, and designed and adapted to be 55 used for stenciling purposes only, whether used in conjunction with a hand-stamp, a type-writing machine, or any other agent. My invention adds to the ordinary printed character the features of a punctured outline 60 of the same character.

While my improved type is intended especially for use in connection with type-writing machines and hand-stamps, it will readily be seen that its application may be extended to 65 nearly every form of printing and engraving. For example, in the printing of negotiable notes and bonds absolute security against alteration would be obtained by the application of my invention. My use of the word 70 "type," therefore, is not to be understood in its restricted sense, since the term is employed generically, to comprehend the various agents from which an ink-transfer is produced.

75 What I claim as new, and desire to secure by Letters Patent, is—

A type provided with puncturing-points extending beyond the face of its character and producing, when the type is used for 80 printing, an outline of the character by perforations in addition to the ink-impression thereof, substantially as described.

AMOS D. ROOD.

In presence of—
M. J. BOWERS,
J. W. DYRENFORTH.
